UNITED STATES PATENT OFFICE.

CHARLES J. MORITZ, OF EFFINGHAM, ILLINOIS.

ROAD SCRAPER.

Application filed March 31, 1925. Serial No. 19,631.

My invention relates to road scrapers and has to do more particularly with road shoulder trimming machines, an object being to provide an improved and simplified machine of this character having certain features and advantages in construction and operation. More particularly, my improved machine is constructed for use in trimming off the dirt shoulders adjacent to or along-
side the road, as alongside the concrete road where a dirt surface approximately six feet wide is required.

For a better understanding of my invention reference is to be had to the accompanying drawings, in which—

Fig. 1 is a plan view of the preferred form of my improved machine;

Fig. 2 is a longitudinal sectional view along the line 2—2 of Fig. 1;

Fig. 3 is an enlarged view of a portion of the machine showing more particularly the mold board, mounting and rotatable support;

Fig. 4 is a cross-section view along the line 4—4 of Fig. 1, showing more in detail the roller adapted to ride on the cement road so as to keep the mold board cutting knife from scraping on the cement surface;

Fig. 5 is an enlarged view of the adjustable end section of the mold board adapted for sloping off the shoulder; and

Fig. 6 is an enlarged view of the clamping means for fastening the mold board carrying beam to the main frame of the body.

Referring now more in detail to the preferred form of my invention as shown herein, I provide a suitable wheeled body adapted preferably to run on the finished road, usually the concrete section, and adapted to carry the mold board at one side thereof. This body in its preferred form consists of a suitable frame comprising side angle members 7—8 suitably braced at 9—10 and carrying rear wheels 11—12 supported upon a suitable axle 13, preferably rigidly attached to the frame. Steerable wheels are also preferably provided at the front end of the frame, and to this end I use wheels 14—15 pivotally attached to the front axle 16 at brackets 17—18 and having steering arms 19—20 rearwardly extending therefrom and connected by a tie rod 21.

Any suitable steering mechanism may be

provided, but I preferably employ a chain 22 connected to the steering arms 19—20 and passing over pulleys 23—24 and back over a drum 25 carried on the shaft of the steering wheel 26. The chain is held taut by a suitable interposed spring 27, so as to prevent slack in the chain when initially connected or when the steering wheel carrying beam 39 is adjusted in the frame. The steering post carries a notched wheel 28, in the teeth of which a dog 29 rests so as to hold the wheel in its adjusted position.

Now as to the shoulder trimming means, for this purpose I preferably provide a suitable mold board in the form of a curved steel member 30 carrying a scraper or bit 31 adapted to be removed for sharpening or replacement.

The mold board is preferably rotatably adjustable, and to this end I provide a central shaft 35 and a circular supporting frame 32 of angle iron curved downwardly at its ends 33—34 and then forwardly to suitably support the mold board 30, which is attached to the face of one web of the angle.

The mold board is also centrally rotatably supported, and to this end I provide the tubular shaft 35 fixedly held in the end of the bracket sections 37—38, which bracket is clamped to the end of the channel iron 39 by the bolts 38'. By removing the bolt 38' at the outer end of bracket 38, and removing bolt 53 at the front end of the bar 46 and then swinging the mold board longitudinally to the machine, the entire mold board, circle frame and bar 46 may be swung upwardly on the rear bolt 38' so as to permit moving the machine through narrow gateways, barn openings, etc., where it otherwise would not go through. Referring again to channel 39, this is longitudinally adjustably held upon the vehicle frame by the clamps as shown in Fig. 6. These clamps are secured to the side bars of the main frame and each includes a block 40 held upon the web of the angle iron, a clamping block 41 extending down into the channel of the scraper supporting beam 39 and carried by a cross bar 42, all adapted to be clamped together by bolts 43.

Thus to adjust the mold board supporting beam 39 on the vehicle frame, the clamps are

unloosened and the beam adjusted to its proper position, where it is held in place by the clamps just described.

Referring again to the mold board supporting means, the shaft therefor extends downwardly through the bracket 37—38 the lower end of the shaft being loose in a bracket 44 fastened to the rear face of the mold board and then extending upwardly 10 through the draw bar bracket 45 carried at the rear end of the draw bar 46.

Thus the mold board is rotatably supported upon the shaft 35 through the bracket 44, and is not only held in an adjusted position 15 through the circular frame 32, but the latter frame also takes the strain off of the shaft 35 which would otherwise be imposed thereon from the scraping operation of the mold board as the machine is drawn along. Thus 20 the draw bar 46 not only takes this strain, but also takes the direct pull upon the mold board instead of this strain being taken by the cross beam 39. The draw bar 46 is pivotally attached at its forward end 53 to the 25 front cross bar 54 of the main frame.

To hold the mold board in its angular adjustment I provide spaced holes 55 in the circular frame 32, so that the frame may be clamped to the draw bar 46 by a bolt 56.

30 In using the present machine for trimming the dirt shoulder adjacent the road, as where such a dirt shoulder is required alongside a concrete roadway, the usual requirement is that this shoulder be trimmed off 35 level with the surface of the roadway, and to this end I provide a roller 57 carried at the inner end of the mold board and adjusted so as to ride upon the road and just maintain the scraper 31 clear of the surface. Thus the 40 scraper is maintained at the proper level and also kept clear of the road so as to prevent wear of the scraper or scraping of the roadway surface. This roller 57 is carried upon an arm 58, pivotally supported by a bracket 45 45 attached to the rear of the mold board, the arm 58 thus permitting the roller 57 to adjust itself according to the angle of the mold board. A set screw 60 is also provided for holding the roller arm in an adjusted 50 position if desired. In connection with the road shoulder being trimmed level with the surface of the roadway, it is usually required that this shoulder be sloped off and kept at a definite width, ordinarily six feet, and then 55 sloping downwardly and outwardly either toward the ditch or so as to form a ditch.

Therefore I have provided an adjustable end for the mold board in the form of a shoulder wing comprising an upper section 60 61 corresponding to the mold board 30, and a knife or cutting section 62 corresponding to the blade 31 carried by the main mold board. This shoulder wing is adjustably carried as an extension of the main mold 65 board, so that it may be used as a straight

extension of the mold board to lengthen it or to form the sloping shoulder extension. Therefore this shoulder wing is pivotally supported upon the main mold board by a casting 63 shaped to take the wing section 70 61 which is clamped thereto by the bolts 64, a pivot bolt 65 passing through the main mold board 30, member 63 and shoulder wing 61 as indicated in Fig. 3. This support 63 has an upwardly extending adjusting arm 66 by means of which the wing may be raised and lowered, as indicated by the full and dotted lines in Fig. 5. This adjustment is preferably made from the driver's seat, and to this end I connect the 75 adjusting arm 66 by a link 67 back to a double arm member 47—48 fixedly attached to a hub 49 rotatably supported upon the shaft 35 and free to move independent thereof. These arms 47—48 are then connected by a chain 50, which passes over a drum carried at the lower end of the shaft 51 which has the hand wheel 52 at the upper end thereof. The drum at the lower end of this shaft is similar to the drum 25 used for 80 the steering chain. This shaft 51 also carries a rack and dog to hold it in its adjusted position.

It will be noted that the shoulder wing operating arm 47 has a peculiar shape. This is so arranged that the connection 68 for the operating link 67 will have the most direct pull upon the wing operating arm 66 within the angle of adjustment of the wing arm and the angle of adjustment of the mold board, the latter being shown in Fig. 1 in its most usual position of operation. At the same time the connecting ends of the arms 47—48 are positioned so as to get the most direct pull upon these arms from the chain 50, through the ordinary angle of adjustment of these arms. That is the parts as shown in Fig. 1 are in their ordinary or most usual adjustment, and the arms 47—48 would ordinarily be used or adjusted or moved forward or backward from the position shown. Similarly the connecting point 68 would have a like adjustment back and forth from the position shown. Therefore I set this connecting point back of a line drawn between the axis of shaft 35 and connecting point 47, so that a more equal adjustment and direct pull is secured as the arm 66 and shoulder wing are adjusted.

Any suitable shaft or draw bar may be 120 employed for attaching the machine to the tractor such as is ordinarily employed, and I have shown a draw bar comprising two members 70—71 which meet at their forward end 72 and are attached at their rear ends to the front beam 54 of the main frame. In order to draw the machine with the least side drag, and this of course will vary according to the angular adjustment of the mold board, transverse adjustment thereof, amount of 125 130

dirt to be moved, etc., and therefore I provide a number of holes 73 in the front bar 54 so that the draw bar may be shifted to the proper point at the front of the scraper.

5 What I claim as new and desire to secure by United States Letters Patent is:

1. In a road shoulder trimming machine of the character described, a wheeled vehicle body adapted to be drawn along on the surface of the finished road, a mold board supporting frame extending laterally from the vehicle body, a road shoulder trimming mold board adjustably suspended from said frame, the suspending means being attached to the said suspending frame laterally of the vehicle body and a drawbar transversely adjustable along the front end of the vehicle body to shift the center of pull substantially on the line of the wheels on the mold board side of the vehicle or outside thereof so as to shift the center of pull according to the side drag on the machine when in use.

2. In a road shoulder trimming machine of the character described, a wheeled vehicle adapted to be drawn along on the surface of the finished road, a mold board supporting frame extending laterally from the vehicle body, a road shoulder trimming mold board adjustably suspended from said frame, the mold board suspending means comprising a vertical pivot shaft attached to the suspending frame and to the mold board, a circular frame extending around the axis of the shaft and attached to the mold board with a relatively stationary beam, and clamping means for securing the circular frame to the beam at various angular positions of the mold board for rigidly holding the mold board against angular displacement during operation, said latter beam extending longitudinally with the vehicle body and having an end attached to the body frame to brace the mold board suspending frame.

3. In a road shoulder trimming machine of the character described, a wheeled vehicle adapted to be drawn along on the surface of the finished road, a mold board supporting frame extending laterally from the vehicle body, a road shoulder trimming mold board adjustably suspended from said frame, a shoulder sloping wing adjustably carried at the outer end of the mold board for sloping off the shoulder to a desired degree, a driver's support carried by the vehicle body, means controlled from the driver's support for adjusting the shoulder sloping wing, said latter means comprising a vertical shaft and hand wheel adjacent the driver's seat, an arm rotatably supported upon a vertical axis by the mold board supporting frame, an arm operating connection from said arm to the hand wheel shaft, an upwardly extending arm attached to the shoulder sloping wing, said wing being mounted upon a substantially horizontal axis, and a connection

from said wing arm to the aforesaid arm, whereby the operation of the hand wheel will rotate the first said arm upon its vertical axis to adjust the shoulder sloping wing to desired angles.

4. In a road shoulder trimming machine, a vehicle body comprising a substantially rectangular frame including longitudinal sides and road wheels at the front and rear ends of the body, a transverse beam extending across the center of the body and projecting laterally beyond the body frame and wheels, a front end beam for said frame projecting laterally beyond the body and wheels forward of the projecting end of the central beam, a mold board positioned to one side of the vehicle body and wheels and having a central connection extending upwardly and suspended from the end of the central beam outside the vehicle body and wheels and permitting angular adjustment of the mold board, and a brace beam extending longitudinally outside of the body frame laterally thereof from the front beam to the central or mold board supporting beam.

5. In a road shoulder trimming machine, a vehicle body comprising a substantially rectangular frame including longitudinal sides and road wheels at the front and rear ends of the body, a transversely adjustable beam extending across the center of the body and projecting laterally beyond the body frame and wheels, a front end beam for said frame projecting laterally beyond the body and wheels forward of the projecting end of the central beam, a mold board positioned to one side of the vehicle body and wheels and having a central connection extending upwardly and suspended from the end of the central beam outside the vehicle body and wheels and permitting angular adjustment of the mold board, a brace beam extending longitudinally outside the body frame laterally thereof from the front beam to the central or mold board supporting beam said central or mold board supporting beam being laterally adjustably held by the vehicle frame and said longitudinal brace beam being connected to the front cross beam and the central beam so as to permit such lateral adjustment.

6. In a road shoulder trimming machine of the character described, a substantially rectangular vehicle body frame having road wheels at the front and rear ends thereof, a mold board centrally pivotally suspended from a laterally projecting frame carried by the vehicle body frame so as to position the mold board laterally of the body for trimming the dirt shoulder adjacent the road while the vehicle wheels run upon the finished surface of the road, a cross beam at the front end of the vehicle body and projecting laterally beyond the body frame and wheels, a brace beam extending from the

front cross beam back to the mold board supporting frame, a draw bar for the vehicle, and means for shifting the draw bar along the front cross beam so as to shift the center 5 of pull according to the side drag on the machine when in use.

7. A road shoulder trimming machine including a wheeled frame, a mold board supporting bar, adjustable transversely of the 10 frame, a mold board carried thereby, an adjustable road shoulder sloping wing carried by the mold board, an operator's support carried by the mold board support, and means on the mold board support for adjusting 15 the road shoulder sloping wing without interfering with the adjustment of the mold board support.

8. In a road grader, a wheeled frame, a mold board support arranged beyond one 20 side thereof, a mold board carried thereby a road shoulder sloping wing pivoted to the mold board, a link pivoted to the mold board support to swing about a vertical axis, means for adjusting the link about its axis, 25 and an operative connection between the link and road shoulder sloping wing.

9. A road grader, including a wheeled frame, a horizontal bar extending laterally from the forward end thereof, a mold board 30 supporting bar also extending laterally from the frame, a draw bar connected with the mold board supporting bar and laterally extending bar, and a mold board carried by the draw bar.

35 10. A road grader comprising a wheeled frame, a mold board support extending laterally therefrom and arranged for horizontal adjustment, a draw bar, a vertical shaft extending from the draw bar and pivotally connecting the latter to the mold board support to permit the draw bar to be swung to various angular positions, and a mold board axially adjustable on the shaft.

40 11. A road grader comprising a wheeled frame, a mold board support extending laterally therefrom and arranged for horizontal adjustment, an angularly adjustable draw bar, a vertical shaft extending from the draw bar and pivotally connecting the 45 latter to the mold board support to permit the draw bar to be swung to various angular positions, and a mold board axially ad-

justable on the shaft, and a quadrant having its ends attached to the mold board and provided with a series of aligned openings, and 55 a removable fastening engaged with any one of the openings and the draw bar to lock the mold board in adjusted position about its axis.

12. In a road grader, a wheeled frame, a 60 pair of parallel bars extending laterally from the frame, a draw bar hingedly connected with one of the bars and having its other end detachably connected with the remaining bar, a mold board carried thereby, 65 the draw bar being arranged to be swung parallel to one of the bars and swung upwardly to an out of the way position while the grader is passing through a restricted 70 passage.

13. In a road grader, a wheeled frame, a pair of parallel bars carried by the frame and extending at right angles to the latter and one of which being adjustable transversely of the frame, a draw bar arranged 75 parallel to the frame and having its ends pivotally attached to the parallel bars, and a mold board carried by the draw bar.

14. The combination with a wheeled frame, of a mold board supported at one 80 side thereof, a road shoulder sloping wing supported for angular adjustment on the mold board, a link pivotally supported to swing about a vertical axis, an operative connection between one end of the link and wing, and manually operable actuating 85 means on the frame and operatively connected with the link whereby to swing the latter about its axis to adjust the wing.

15. The combination with a wheeled frame, of a mold board supported at one 90 side thereof, a road shoulder sloping wing supported for angular adjustment on the mold board, a link pivotally supported to swing about a vertical axis, an operative connection between one end of the link and wing, a hand operated rotatable element on the frame, and flexible elements connected 95 with the link and rotatable element whereby to swing the link about its axis to adjust the road shoulder sloping wing.

In witness whereof, I hereunto subscribe my name this seventh day of March, 1925.

CHARLES J. MORITZ.
